(57) **CLAIM**

The ornamental design for a mount for an indicator or instrument, as shown and described.

DESCRIPTION

Cross reference is made to copending U.S. design patent application Ser. No. 29/724,414 entitled "Mount for an Indicator or Instrument" by Daniel Doerr, which was filed on even date herewith; and to copending U.S. design patent application Ser. No. 29/724,415 entitled "Mount for an Indicator or Instrument" by Daniel Doerr, which was filed on even date herewith.

FIG. 1 is a perspective view of a mount for an indicator or instrument showing my new design;

FIG. 2 is a right side elevational view of the mount for an indicator or instrument of FIG. 1;

FIG. 3 is a left side elevational view of the mount for an indicator or instrument of FIG. 1;

FIG. 4 is a top plan view of the mount for an indicator or instrument of FIG. 1;

FIG. 5 is a bottom plan view of the mount for an indicator or instrument of FIG. 1;

FIG. 6 is a front side elevational view of the mount for an indicator or instrument of FIG. 1; and,

FIG. 7 is a rear side elevational view of the mount for an indicator or instrument of FIG. 1.

The broken lines shown in the drawings illustrate portions of the mount for an indicator or instrument that form no part of the claimed design.
